CLAIM

The ornamental design for a travel organizer, as shown and described.

DESCRIPTION

FIG. 1 is a top, front, right perspective view of a travel organizer showing our new design;

FIG. 2 is a top view thereof;

FIG. 3 is a bottom view thereof;

FIG. 4 is a front view thereof;

FIG. 5 is a rear view thereof;

FIG. 6 is a left side view thereof;

FIG. 7 is a right side view thereof;

FIG. 8 is a top, front, right perspective view of an alternative claimed configuration of a travel organizer showing our new design;

FIG. 9 is a top view thereof;

FIG. 10 is a bottom view thereof;

FIG. 11 is a front view thereof;

FIG. 12 is a rear view thereof;

FIG. 13 is a left side view thereof; and,

FIG. 14 is a right side view thereof.

The even length broken length lines represent stitching and form no part of the claimed design.

1 Claim, 14 Drawing Sheets
